UNITED STATES PATENT OFFICE.

JOHN C. KOCH, OF BERLIN, GERMANY.

ALBUM-CLASP.

SPECIFICATION forming part of Letters Patent No. 252,226, dated January 10, 1882.

Application filed July 5, 1881. (No model.)

To all whom it may concern:

Be it known that I, JOHN C. KOCH, a citizen of the United States, residing in Berlin, Germany, have invented an Improvement in Album-Clasps, of which the following is a specification.

Album-clasps have been made in two parts that are acted upon by a screw, so as to adapt them to different thicknesses of books.

10 My invention is made with reference to simplicity of construction and to rendering the clasp ornamental and preventing the screw being visible at either side of the clasp.

In the drawings, Figure 1 is a face view of 15 the clasp, partially in section; and Fig. 2 is a section at the line *x x*.

The clip-pieces *a* and *b*, that are to be secured to the edges of the album or book-cover, are made of any desired shape so as to be attached by rivets or otherwise. Upon the clip-piece *a* there is a hinge, *c*, that connects it to 20 the box *d*, that is made preferably with a removable cap-plate, 2, and guide-slides 3, and *e* is a sliding frame forming the movable portion 25 of the extension-clasp. This frame *e* has a bow or loop that catches over the stud *i* upon the clip-piece *b*, or connects with any other fastening on this clip-piece, and said frame *e* also has a cross-bar, 5, within the box *d*, and 30 through this cross-bar the screw *r* passes.

Said screw can be revolved; but its head 6 at one end and a rivet or spread end at the other prevent end movement to the screw. Hence, when said screw is revolved by turning the head 6 between the thumb and finger, the cross-frame *e* is moved to extend or contract the clasp. In this movement the cross-bar 5 is moved sidewise, and the parallel portion of the frame slides endwise within the guide-slides 3.

The cap-plate can be fastened on by screws 35 or otherwise, and the clasp can be extended or contracted at pleasure, either to suit different sizes of books or to hold the book closed more or less tightly.

I claim as my invention—

The combination, in a book-clasp, of the clips *a* and *b*, the box *d*, hinge *c*, connecting the same to the clip *a*, the frame *e*, having a cross-bar within the box, the screw *r*, also within the box, and passing through the cross-bar, 40 and having a head, 6, outside the box, by which it can be revolved, substantially as set forth.

In testimony whereof I have signed my name to this specification in the presence of two subscribing witnesses.

JOHN C. KOCH.
